UNITED STATES PATENT OFFICE.

ANTON FOLLSTAD, OF ELCHO, WISCONSIN.

DESIGN FOR A SKATE.

SPECIFICATION forming part of Design No. 31,052, dated June 20, 1899.

Application filed May 23, 1899. Serial No. 717,959. Term of patent 7 years.

To all whom it may concern:

Be it known that I, ANTON FOLLSTAD, a citizen of the United States, residing at Elcho, in the county of Langlade and State of Wisconsin, have invented and produced a new and original Design for Skates, of which the following is a specification, reference being had to the accompanying drawing, forming part thereof, and in which the figure is a perspective view of a skate, showing my new design.

The leading feature of my design consists in the skate forming the subject-matter of the accompanying illustration.

The body A of the skate is curved inwardly at its middle in its opposite sides, and the runner or blade B presents a broad surface in cross-section and is extended in advance of

the body A and has the upper edge of its forwardly-extended portion curved inwardly at B', its edge plate C conforming to the edge 20 curvature of the blade and overlapping at C' the upper front edge of the body A.

The special purpose of the invention is to furnish a snow-skate or street and coasting 25 skate.

Having described my invention, what I claim as new, and desire to secure by Letters Patent, is—

The design for a skate as herein shown and described.

ANTON FOLLSTAD.
